(74) Attorney, Agent, or Firm — BrownWinick Law Firm;
Jordan Meggison-Decker(57) **CLAIM**

The ornamental design for a fire nozzle, as shown and described.

DESCRIPTION

FIG. 1 is a left side view of a fire nozzle showing my new design;

FIG. 2 is a right side view of the fire nozzle;

FIG. 3 is a rear view of the fire nozzle;

FIG. 4 is a front view of the fire nozzle;

FIG. 5 is an additional left side view of the fire nozzle;

FIG. 6 is an additional right side view of the fire nozzle; and,

FIG. 7 is a top front side perspective view of the fire nozzle. The fire nozzle is shown with a break to indicate non-specified length. The appearance of any portion of the article between the break lines forms no part of the claimed design.
